UNITED STATES PATENT OFFICE.

GEORGE E. HOFFMAN, OF ROCKFORD, ILLINOIS.

COMBINATION WINDOW SHADE AND CURTAIN HOLDER.

Application filed April 1, 1925. Serial No. 19,761.

This invention relates to a combination window shade and curtain holder and among the objects thereof are to provide a novel device for supporting a shade roller and including a curtain holder in which the parts are primarily constructed in a simple and inexpensive manner of sheet metal capable of being readily assembled and which will lend itself to economical production; to provide novel means for adjusting the holder or bracket for attachment to windows of different widths by engagement with the moldings of the frames thereof; to slidably interfit or mount the parts of the device for telescopic movement so that they may be easily adjusted; and to provide novel means by which the bracket or holder may be firmly held or clamped in an adjusted position as applied to a particular size of window frame.

Other objects and attendant advantages will be appreciated by those skilled in this art as the invention becomes better understood by reference to the following description when considered in connection with the accompanying drawings, in which—

Figure 1 is a plan view of the novel combination window shade and curtain holder or bracket mounted in position for use.

Fig. 2 is a front elevation of the device or structure shown in Fig. 1.

Fig. 3 is an enlarged sectional elevation taken on the line 3—3 of Fig. 1.

Fig. 4 is a sectional elevation of a modified form of bracket for supporting a shade roller and a curtain pole.

Fig. 5 is an enlarged sectional view taken on the line 5—5 of Fig. 1; and

Fig. 6 is a front elevation of the construction shown in Fig. 5.

Referring to the drawings in detail wherein I have illustrated an embodiment of the invention and in which similar reference characters designate corresponding parts throughout, 7 designates a window frame for the window 8, 9 the side moldings and 10 the top molding of the frame to which the novel combination window shade and curtain holder or bracket of my invention is applied.

The device consists of two relatively flat tubular sections 11 and 12 telescopically or slidably interfitted one over the other, said tubular sections being substantially of channel or reverse C-shaped cross-section as clearly shown in Figs. 3 and 5 of the drawings. This provides a front portion 13, top

and bottom curved or bent portions 14 and edge flanges 15 extending in opposite directions upwardly and downwardly and spaced apart to provide a slot 16.

In order to mount these sections on the window frame, short tubular sections 17 are fitted on the outer ends of the sections 11 and 12 and are formed from blanks of sheet metal or the like bent in channel shaped formation and the upper and lower ends being bent rearwardly and downwardly and substantially brought together as indicated at 18 in Fig. 3. The end of the blank intermediate the upper and lower extremities is bent rearwardly and then inwardly as indicated at 19 to extend around the ends of the top moulding 10 of the frame and then inwardly behind the same where they are anchored by means of prongs 20 on the extremities of the inwardly directed portions. Suitable fastening means such as bolts 21 are passed through registering holes in the front walls of the tubular sections 17 and the sections 11 and 12 on which they are mounted, thus securely anchoring the parts.

It will be seen that the sections 11 and 12 are substantially held by friction between their interfitted walls, but in order to positively insure that the holder or bracket will be held in adjusted position when mounted on a window frame or the like for use, clamping means 22 is provided. This clamping means consists of a tubular member corresponding in cross-section to the sections 11 and 12 and snugly fitting over the outer section 12. However, the extremities of the legs 23 thereof are directed inwardly and then outwardly in angular relation as indicated at 24 against the faces of the leg portions of the inner section 11 as clearly shown in Fig. 5 of the drawings. By this means the clamping section 22 is prevented from turning on the interfitted sections 11 and 12. The front wall of the clamp 22 is stamped or cut at two points along the two horizontal lines 25 and an intermediate vertical line, the parts of the metal being struck up or bent in outstanding relation to provide pivot ears 26 as seen in Figs. 5 and 6. These ears are apertured to receive the pivot ends 27 of a wire clamp 28 consisting of a single section or length of wire or the like rebent intermediate of its ends and having the legs thereof curved on a graduating arc as indicated at 29 and the ends then extended outwardly to engage the

apertures of the ears 26 as indicated at 27. It will thus be seen that the portions 29 form cams which frictionally engage the front wall of the section 12 when turned 5 down as indicated in Figs. 5 and 6, thus forcing the front wall of the section 12 against the corresponding wall of the section 11 to clamp the parts in adjusted position according to the length of bracket required 10 for a window frame and bracket of a particular window width. Of course, it is to be understood that the device is made the required length to permit it to be applied to the window frame and then shortened by 15 telescoping the sections 11 and 12, after which the clamp 28 is applied to hold the bracket in position.

In order to support a shade roller and shade carried thereby, as well as curtains, 20 bracket arms 30 are provided. These brackets consist of strips of metal having short tubular portions 31 corresponding in cross-section to the sections 17 and mounted on the sections 11 and 12. Since the sections 31 25 snugly fit the sections 11 and 12 and are of corresponding cross-section, they will be frictionally held in adjusted position thereon. The brackets 30 are provided with the usual opening and slot as indicated at 32 and 33 to accommodate the ends of the shade roller 34. As seen in Fig. 3, the extremities of the brackets 30 are tapered and have vertical portions 35 forming upper and lower extensions 36, preferably with rounded 30 ends, to take a curtain holder 37. This curtain holder corresponds in cross-section substantially to the sections 11 and 12 so as to fit the vertical portion 35 and the rounded ends 36. It comprises sections 38 and 39 35 telescopically fitted one within the other and having their extremities curved rearwardly as indicated at 40 if so desired, so that the curtain will envelop and cover the entire holder or bracket and conceal the same from 40 view. In view of the cross-section of the parts 35 and the sections of the curtain holder the latter may be tilted or turned at an angle vertically to align the slots thereof with the part 35 so that the sections 38 45 and 39 may be readily engaged or disengaged from the brackets 30. This facilitates assembly and dismounting of the parts. In Fig. 4 of the drawings a modification of the shade bracket is shown at 41 corresponding to the cross-section shown at 3—3 except that the tapered end 42 thereof is provided with a concave recess 43 for receiving a curtain support or pole 44 adapted to take rings 55

or other means provided for the attachment of the curtain thereto and suspension therefrom. It will be noted from Figs. 3 and 4 that the flanges of the tubular portions 17 of the brackets may be disposed in over-lapped relation as indicated at 45, the resiliency 60 of the metal causing these parts to frictionally contact and retain the brackets in adjusted positions as well as to prevent any possibility of angular vertical movements 65 thereof on the supporting member formed by the sections 11 and 12. 70

While I have described what I now consider to be the preferred embodiment of the invention, it is to be understood that the device is susceptible of wide changes and variations in the construction, arrangement and purposes of the parts as well as the materials used, without departing from the spirit and scope of the invention as will be hereinafter defined in the claims. 75

I claim:

1. In a means for supporting the ends of a window shade roller and curtain rod in substantially parallel relation, a bracket formed from sheet metal to provide a supporting portion at the inner end thereof and provided with a recess intermediate the ends thereof for the shade roller, and having the outer end conformed with a flat substantially vertical face edge arranged to lie against the inside of a flat substantially channel shaped curtain rod, and having a lug projecting upwardly at the top of said face edge arranged to engage within the rod in a recess provided in the upper flange of said channel shaped rod whereby to detachably secure and support said rod on said bracket. 80 85 90 95

2. In a means for supporting a window shade roller and a curtain rod in substantially parallel relation, said rod being flat and substantially channel shaped in cross-section with the upper and lower flanges thereof bent inwardly toward each other to approximate a C-shape, a bracket for supporting the ends of said shade roller and curtain rod, formed from sheet metal to provide a supporting portion at the inner end thereof and provided with a recess intermediate the ends thereof for the shade roller and having the outer end conformed in an approximately T shape to detachably secure and support the same on said rod while permitting endwise adjustment of said rod with respect to said bracket. 100 105 110

GEORGE E. HOFFMAN.
